UNITED STATES PATENT OFFICE.

LERoy BAUMGARTL, OF CHICAGO, ILLINOIS.

DEMOUNTABLE WHEEL.

1,353,511.

Specification of Letters Patent. Patented Sept. 21, 1920.

Application filed March 27, 1917. Serial No. 157,781.

To all whom it may concern:

Be it known that I, LEROY BAUMGARTL, a citizen of the United States, residing at Chicago, in the county of Cook and State of Illinois, have invented a new and useful Improvement in Demountable Wheels, of which the following is a specification.

My invention relates, more particularly, to wheels involving an inner hub-member adapted to be driven, in the case of a drive-wheel, in which case, it would be connected with a drive-mechanism, or mounted in bearings to rotate freely when it is not a drive-wheel; an outer hub-member adapted to telescope with the inner hub-member and to which the spokes of the wheel are connected; and means for releasably holding the outer hub-member in such relation to the inner hub-member that these two members will operate as a unit.

My primary object is to provide a novel and simple construction of wheel of the character above referred to, which will permit the outer hub-member and the parts carried thereby to be easily and quickly assembled with, and removed from, the inner hub-member and which will be strong in construction and positive in operation.

Referring to the accompanying drawings, Figure 1 is a view in longitudinal sectional elevation of the hub-portion of a wheel constructed in accordance with my invention, the hub-members being shown in assembled relation; Fig. 2 is a broken section taken at the line 2 on Fig. 3 and viewed in the direction of the arrow; Fig. 3 is a section taken at the irregular line 3 on Fig. 1 and viewed in the direction of the arrow, showing the clips in elevation; Fig. 4 is a broken sectional view taken through the flanges of the inner and outer hub-members and showing means for initially separating the hub-members in the disassembling operation; Fig. 5 is a face view of a cam-equipped ring forming a part of the locking mechanism for the wheel; Fig. 6 is a broken section taken at the line 6 on Fig. 4 and viewed in the direction of the arrow, this view showing a detail of the means for rotatably adjusting the cam-ring; and Fig. 7, a view in elevation of the pinion-equipped shaft, through the medium of which the cam-ring is actuated.

The inner hub-member of the wheel is represented at 6, it being understood that this hub-member may be of any internal form desired to adapt it to serve as a hub of

a drive-wheel or a driven wheel of a vehicle, this part of the wheel structure in practice remaining attached to the vehicle, namely to the driving-axle of the vehicle 60 when the wheel is a drive-wheel and journaled on a stationary axle when the wheel is not one of the drive-wheels of the vehicle. The outer hub-member of the wheel is represented at 7, this hub-member in practice 65 being connected with spokes (not shown), to the outer extremities of which the felly (not shown) would be attached, whereby this outer hub-member, the spokes and felly referred to would thus be connected together 70 and the whole adapted to be bodily removed from, and assembled with, the inner hub-member 6, as desired, the outer hub-member 7 being hollow and adapted to telescope with the inner hub-member.

In the particular embodiment illustrated, the outer end of the inner hub-member 6 is of frusto-conical form, providing the tapered, or wedge, surface 8, and its inner end carries an annular flange represented at 9. 80 The internal form of the hub-member 7 is such that it will snugly fit the tapered portion 8 of the hub-member 6 when assembled therewith, the inner end of the hub-member 7 being equipped with an angle-shaped 85 flange 10, the portion 11 of which extends substantially parallel with the flange 9 and is spaced therefrom, as shown, and the annular portion 12 of which overlaps the periphery of the flange 9, thus forming with the flanged portion 9 of the inner hub-member 90 an annular housing about the latter.

The portion 11 of the outer hub-member 7 is provided, preferably at equal intervals, with a series of pins 13 which extend laterally from the flange 11, in a direction generally lengthwise of the hub, and into sockets 14 provided in thickened portions 15 of the flange 9 at its inner side. The pins 13 are rigidly held in position on the flange 11 by 100 means of the flanges 16 and 17 interlocking with the inner and outer faces of the flange 11, these pins and the sockets 14, in the particular illustrated embodiment of the invention, being of such form and size that the 105 inner ends of the pins 13 will snugly fit in the sockets 14 when the inner and outer hub-members are assembled to the position shown in Fig. 1. It may be here stated that according to the preferred illustrated embodiment of the invention the pins 13 operate to 110 hold the inner and outer hub-members to

gether against relative rotation, and this holding or locking action is supplemented by a second series of pins 17, which are rigidly secured to the flange 9 to extend laterally therefrom to the right in Fig. 1 and into sockets 18 in the flange 11 when the parts of the hub are assembled.

In accordance with my invention, means are provided for forcibly drawing the outer hub-member upon the inner hub-member, to cause the former to snugly fit the periphery of the latter, these means, in the particular construction shown, comprising a ring 19 journaled upon the annular surface 20 concentric with the axis of the wheel, and held in place by extending into grooves 21 arranged in a continuous series about the surface 20, these grooves being formed in bosses 22, preferably of a number corresponding with the number of pins 13, which, in the case of the construction shown, is three. The ring 19 is provided at intervals about its periphery with cam means which cooperate with shouldered portions 23 on the pins 13 and which operate in the rotation of the ring in one direction to cam the pins 13 to the left in Fig. 1, thus drawing the hub-member 7 upon the hub-member 6. The construction of the cam means referred to, as I prefer to provide them, involves the provision of tangentially-disposed cam-surfaces 24 and 25 arranged in pairs, as shown in Fig. 5, about the periphery of the cam-ring 19, these cam-surfaces 24 and 25 of each pair converging relative to each other, as shown, and preferably beveled, as indicated at 26 and 27, respectively, to provide broadened surfaces for co-operation with the shouldered portions 23, which preferably have their surfaces which oppose the surfaces 26 and 27 of the ring 19, beveled, as indicated at 28. The beveled surfaces 26 and 27 are preferably uniformly beveled throughout their length, and in riding from their low points, indicated at 29 in Fig. 5, to their high points, against the beveled surfaces 28 of the pins 13, operate to force these pins, and with them the outer hub-member 7, to the left in Fig. 1, on the inner hub-member 6. The provision of the cam surfaces 24 and 25 in pairs, as shown, for co-operation with the shouldered parts 23 at opposite sides of the pins 13, is of advantage inasmuch as thereby the pressure exerted by the cam-ring in adjusting it as hereinafter stated, is applied substantially equally at opposite sides of the pins, which prevents tendency of the pins to cant.

In order to prevent springing of the portions of the ring having the cam surfaces 25, I provide clips 30 secured to the inner face of the flange 9, as by the screws 31, these clips containing grooves 32 which serve as guides for the said portions of the ring.

65 In the particular construction illustrated

the cam-ring 19 is adapted to be moved into and out of the position shown in Fig. 3 to lock the hub-members together, and permit them to be disassembled, respectively, by means of a pinion 33 meshing with a segmental rack 34 provided on the periphery of the ring 19. The pinion 33 is rigid with a shaft 35, journaled at its headed portion 36 in an opening 37 in the flange 9, and at its opposite end in an opening 38 in the flange 11, this end of the shaft projecting laterally beyond the flange 11 to adapt it to be rotated, as by means of a wrench or other tool applied to its squared portion 39. The shaft 35 is longitudinally movable, with the pinion 33, in its bearings, a coil-spring 40 being provided between the flange 9 and an end of the pinion 33 for normally forcing this shaft and pinion to the right in Fig. 6, the opposite end of this pinion and the opposing face of a boss 41 on the flange 11 surrounding the bearing 38, being provided with co-operating ratchet teeth 42.

In assembling the parts of the structure, the ring 19 is first applied to position on the hub-member 6, the inner periphery of the ring containing notches 43 adapting it to be passed over the bosses 22 into registration with the grooves 21 therein, the operator then rotating the ring in clockwise direction, in Fig. 3, to a position in which depressions 44 in the periphery of the ring adjacent the low points 29 of the cams, are coincident with the dished portions 45 of the bosses 22, the parts of the ring 19 carrying the cams 25 entering the grooves 32. The pins 17 are then secured in the flange 9 in the position shown in Fig. 2 and the pinion 33, with its shaft 35, is then assembled with the inner hub-member and ring 19 as shown in the drawings. With the ring 19 rotatably adjusted on the hub-member 6, as stated, the hub-member 7 is telescoped with the member 6, the shouldered portions 23 of the pins 13 passing through the recesses 44 and 45, and the inner ends of the pins 13 entering the sockets 14, in this operation, and the pins 17 entering the openings 18. The operator then rotates the ring 19 in a counter-clockwise direction in Fig. 3 by rotating the pinion 33, the portions of the ring carrying the cams 25 sliding in the grooves 32 and the pairs of cams moving against the shouldered portions 23, as explained, to force the hub-member 7 into rigid interlocking engagement with the hub-member 6.

In practice the rings 19 would be provided as rights and lefts for the wheels at opposite sides of the vehicle, and each ring would be so arranged with the other parts of the wheel that the tendency of the wheel in rotating will be to draw the ring 19 into closer engagement with the shouldered portions 23 of the pins 13, and in addition to this the ratchet teeth 42 on the pinion 33

and boss 41 would be so arranged that while the pinion 33 would be free to rotate when the ring 19 moves in a counter-clockwise direction in Fig. 3, this pinion cannot rotate in the opposite direction until the operator 5 disengages the teeth 42 by pushing the shaft 35 inwardly, and thus the ring 19 is locked against accidental loosening.

In the particular construction illustrated 10 provision is also made for initially forcing the hub-member 7 from the hub-member 6 to make its removal easy when it is desired to remove the outer hub-member from the inner hub-member, the means as shown for 15 this purpose comprising cam means between the ring 19 and the flange 11, which are so arranged that in the final rotary movement of the ring 19 in a clockwise direction in Fig. 3 to a position in which the recesses 20 44 register with the recesses 45, the hub-member 7 is forced to the right in Fig. 1 a relatively slight distance. These means as shown comprise bosses 46 and 47 on the flange 11 and ring 19, respectively, arranged 25 in pairs about the axis of the hub, as shown in Fig. 4, and having beveled faces 48 and 49, respectively, which mutually engage and produce the camming action as, and at, the time stated.

30 While I have illustrated and described a particular construction in which my invention is embodied, I do not wish to be understood as intending to limit it thereto, as the same may be variously modified and altered 35 without departing from the spirit of my invention, it being my intention to claim my invention as fully and completely as the prior state of the art will permit.

What I claim as new and desire to secure 40 by Letters Patent is:

1. In a structure of the character set forth, the combination of an inner hub-member and an outer hub-member, a pin carried by one of said members and extending 45 lengthwise of said hub, the other of said members containing a socket, said pin having a shouldered portion and extending at its end into said socket for locking said hub-members against relative rotation, and 50 cam means adjustably supported on the one of said hub-members containing said socket, for coöperation with said shouldered portion and operating to draw said hub-members together and hold them against longitudinal separation, said socket and shouldered portion being located at the same side 55 of said cam means.

2. In a structure of the character set forth, the combination of an inner hub-member and an outer hub-member, one of 60 said hub-members being provided with a shoulder, a third member mounted on the other of said hub-members to be movable thereon and equipped with a cam adapted 65 to coöperate with said shoulder and operat-

ing upon shifting said third member to draw said hub-members together and hold them against longitudinal separation, a gear for actuating said third member, and means for releasably holding said gear 70 against rotation in a direction contrary to that for forcing said hub-members together.

3. In a structure of the character set forth, the combination of an inner hub-member and an outer hub-member, one of 75 said hub-members being provided with a shoulder, a third member mounted on the other of said hub-members to be movable thereon and equipped with a cam adapted to coöperate with said shoulder and operating 80 upon shifting said third member to draw said hub-members together and hold them against longitudinal separation, a longitudinally movable shaft, a gear on said shaft for actuating said third member, and 85 means for releasably holding said gear against rotation in a direction contrary to that for forcing said hub-members together.

4. In a structure of the character set forth, the combination of an inner hub-member and an outer hub-member, said outer hub-member being provided with a shoulder, projections on said inner hub-member radiating therefrom and containing 90 ring-guiding grooves, and a ring containing recesses in its inner periphery adapted to register with said projections and adapting said ring to be applied to said inner hub-member to engage said ring-guiding grooves upon rotating said ring, said 95 ring being provided with a cam surface adapted to coöperate with said shoulder and operating to force said hub-members together when said ring is rotated in one direction.

5. In a structure of the character set forth, the combination of an inner hub-member and an outer hub-member, flanges on said hub-members forming a housing, the flange on said inner hub-member containing sockets in its inner face, pins projecting laterally from the flange on said outer hub-member and into said housing and extending into said sockets, said pins having shouldered portions, and a ring in 110 said housing rotatably mounted on said inner hub-member and having cam surfaces which oppose, and coöperate with, said shouldered portions and operate when said ring is rotated in one direction, to force 115 said pins and said outer hub-member lengthwise of said inner hub-member to draw said hub-members together.

6. In a structure of the character set forth, the combination of an inner hub-member and an outer hub-member, one of 120 said members being provided with a shoulder, and a third member supported on the other of said members to be shiftable thereon and having a pair of converging cam 125

surfaces, said cam surfaces being beveled transversely of their length.

7. In a structure of the character set forth, the combination of an inner hub-member ⁵ and an outer hub-member, one of said members being provided with a beveled shoulder, and a third member supported on the other of said members to be shiftable thereon and having a pair of converging cam surfaces for engaging said beveled shoulder, said cam surfaces being beveled transversely of their length.

8. In a structure of the character set forth, the combination of inner and outer tapered ¹⁰ telescoping hub-members, a pin carried on

the end of said outer hub-member extending lengthwise of the structure, said pin being provided with a shoulder, a ring rotatably mounted on said inner hub-member between the ends of the latter for engaging the ²⁰ shouldered-portion of said pin to draw said hub-members together when said ring is rotated in one direction, and said inner hub-member containing a socket into which said pin extends when said hub-members are ²⁵ drawn into telescoped relation by the operation of said ring, for preventing relative rotation of said hub-members.

LEROY BAUMGARTL.
